UNITED STATES PATENT OFFICE.

WILLIAM F. HAUSSTEIN, OF LYNDHURST, NEW JERSEY, ASSIGNOR TO THE KEUFFEL & ESSER COMPANY, OF HOBOKEN, NEW JERSEY, A CORPORATION OF NEW JERSEY.

CALCULATING-MACHINE.

No. 882,679.

Specification of Letters Patent. Patented March 24, 1908.

Application filed November 9, 1904. Serial No. 232,028.

To all whom it may concern:

Be it known that I, WILLIAM F. HAUSSTEIN, a citizen of the United States, residing at Lyndhurst, in the county of Bergen 5 and State of New Jersey, have invented certain new and useful Improvements in Calculating-Machines, of which the following is a specification.

This invention relates to calculating machines such as that which forms the subject 10 matter of U. S. patent to Alexander Rechnitzer, No. 809,075, granted Jan. 8, 1906.

In that machine the various operations of 15 addition, subtraction, multiplication and division are performed and the machine comprises in its mechanism a starting lever which to start the machine to multiply must be moved to one end of a slot through which it projects, while to start the machine to divide, 20 it must be moved to the opposite end of the slot, and it must be retained in such position during the operation, an accidental displacement during an operation leading to disastrous results in disarranging or breaking the 25 calculating mechanisms.

The original machine contained no mechanism for retaining the starting lever in the 30 positions for starting these operations of multiplication or division and the special object of this invention is to supply this deficiency and to render it practically impossible to displace the starting lever from these starting positions during either of these operations.

With these objects in view this invention 35 consists in providing such a machine with an automatic safety clutch and release mechanism whereby the starting lever will be engaged and held in the starting position for multiplication or division, will be retained 40 therein during the operation, and will be automatically released at the termination of the operation.

In the accompanying drawings in which is 45 illustrated the mechanism comprising the present invention and so much of the adjacent mechanism as is necessary to a complete understanding of its construction and operation, Figure 1 is a top plan view of the 50 stationary part of the machine and sliding carriage, parts thereof being broken away and parts shown in dotted lines. Fig. 2 is a bottom plan view of the clutch engaging the starting lever in either position, one of the

positions being shown in dotted lines. Fig. 3 55 is a similar view with the slide moved to disengage the starting lever. Fig. 4 is a view in front elevation.

In the drawings 5 indicates the top of the 60 stationary part of the machine and 6 the top of the sliding carriage, the stationary part supporting the starting lever and clutch mechanism and the sliding carriage carrying the terminal pin, subject of this application. The base of the stationary part is indicated 65 at 7 and upon it are erected bearings 8 for a rock-shaft 9 to which the starting lever 10 is secured, said starting lever projecting up through a slot 11 in the top 5. The starting lever is moved longitudinally of the machine 70 to the end 12 to start the machine to perform the operation of multiplication and to the end 13 to start the machine to perform the operation of division, the rock-shaft 9 sliding as the lever is thus moved. Branch 75 slots 14 and 15 are provided into which the starting lever is moved (by rocking the shaft 9), into the branch slot 14 to start the adding operation and into the branch slot 15 to start the subtracting operation. 80

The object of this invention being to provide mechanism for securing the starting lever in the positions for starting the multiplication and division operations, the other mechanisms, some of which are illustrated in 85 the drawings, will not be further referred to.

On the under face of the top 5 adjacent to the slot 11 is secured the clutch mechanism of which 16 is a spring bearing upon the outer end of a pawl 17 pivoted at 11 with a tendency to keep that end against a stop pin 18 and the inner end, which is provided with a tooth 19, in position to be engaged by the starting lever when said lever is moved into the end 13 to start the division operation, the 95 starting lever carrying a spline or tooth 20 which depresses and drops behind the tooth 19 to retain the lever in this starting position. At 21 there is provided another pawl 22 which is in turn provided with a tooth 23 100 which bears the same relation to the starting lever and its tooth 20 (when the lever is moved to end 12 of the slot to start the division operation) as the pawl 17 and its tooth 19 bears to such parts in the multiplication 105 starting position before described.

To the top 5 at 24 is pivoted a disk 25 which is connected by a wrist pin 26 and a

link 27 to the pawl 17 and by a wrist pin 28 and link 29 to the pawl 21 so that the tooth ends of both pawls are yieldingly and normally held in position to receive and engage 5 the starting lever when moved to either of the ends 12 or 13 of slot 11 to start the machine, and so that one releasing mechanism will simultaneously operate both pawls to release the starting lever from either position.

On the underside of the top 5 is a plate 30 slidably secured by screws 31 passing through a slot 32 into top 5, said slotted plate having a projection 33 outside the edge 15 of top 5 in the line of travel of a pin 34 (which I denominate a terminal pin) carried by the sliding carriage. When the machine is performing the operation of division, this terminal pin is inserted in a hole 35 and when multiplication is being performed, in a hole 36, said holes being in the sliding carriage.

The terminal pin being in, say hole 35, the handle is moved to end 12 of the slot 11, when the machine will start to perform an 25 operation in division, the carriage sliding to the right during such operation. When the terminal pin at the end of the operation strikes the projection 33 of plate 30, it moves said plate to the right against an arm 37 of 30 pawl 21 which tips the pawl, thus drawing on link 29, turning disk 25, drawing on link 27 and withdrawing the tooth of pawl 17 out of contact with the starting lever leaving said 35 lever free to be moved as may be desired to start another operation. In the operation of multiplication, the terminal pin in hole 36, at the end of the operation, strikes projection 33 of plate 30, and causes it to actuate plate 30 against arm 37 of pawl 21, which tips the 40 pawl and removes its tooth out of contact with the starting lever leaving the lever free to be moved to any desired position to start another operation.

What I claim as new is:—

- 45 1. In a calculating machine provided with a plate having a slot therein, a slidable shaft, a lever secured to the shaft, projecting through the slot and adapted to be moved from a normal intermediate position to either 50 end of said slot, and a pawl automatically operated to secure the lever against accidental movement from either end position.
2. In a calculating machine provided with a plate having a slot therein, the combination therewith of a lever adapted to be moved to either end of said slot, a pawl automatically operated to secure the lever against accidental movement from either of such positions, a sliding carriage, an adjustable stop 60 thereon, and means actuated by said stop at

the termination of the carriage movement to release the pawl.

3. In a calculating machine the combination with the stationary top provided with a slot having an end space, a starting lever 65 adapted to be moved into said end space to start the machine, a pawl normally in position to secure the starting lever in such position, a sliding carriage, a terminal pin thereon, a slideable plate on the stationary portion 70 of the machine in the path of the pin, and connections whereby the pawl, at the termination of the operation of the carriage, is released by said slideable plate.

4. In a calculating machine the combination with the stationary top provided with a slot having two end spaces, a starting lever 75 adapted to be moved into either of said end spaces to start the machine, two pawls normally in position to secure the starting lever 80 in either of such positions, a sliding carriage, a terminal pin thereon, a slideable plate on the stationary portion of the machine in the path of the pin, and connections whereby the pawls, at the termination of the operation of the 85 carriage, are released by said slideable plate.

5. In a calculating machine the combination with the stationary top provided with a slot having an end space, a starting lever 90 adapted to be moved into said end space to start the machine, a pawl normally in position to secure the starting lever in such position, a disk pivoted to the stationary top 95 of the machine, a link connecting it with the pawl, a sliding carriage, a terminal pin thereon, a slideable plate on the stationary portion of the machine in the path of the pin, and connections whereby the pawl, at the termination of the operation of the carriage, is released by said slideable plate.

6. In a calculating machine the combination with the stationary top provided with a slot having two end spaces, a starting lever 100 adapted to be moved into either of said end spaces to start the machine, two pawls normally in position to secure the starting lever 105 in either of such positions, a disk pivoted to the stationary top of the machine, two links connecting it with the pawls, a sliding carriage, a terminal pin thereon, a slideable plate 110 on the stationary portion of the machine in the path of the pin, and connections whereby the pawls are released by said slideable plate.

In testimony whereof I affix my signature in presence of two witnesses.

WILLIAM F. HAUSSTEIN.
